CLAIM

The ornamental design for a settee, as shown and described.

DESCRIPTION

FIG. 1 is a perspective view of my design for a settee; FIG. 2 is a front elevational view of the settee; FIG. 3 is a rear elevational view of the settee; FIG. 4 is a view of one side of the settee; FIG. 5 is a view of the opposite side of the settee; FIG. 6 is a top plan view of the settee; FIG. 7 is a bottom plan view of the settee; and, FIG. 8 is a perspective view of my design for a settee which is the same as that shown in FIG. 1 and has the same design motif except that the settee is of greater length.

FIG. 1

FIG. 2**FIG. 3****FIG. 5****FIG. 4****FIG. 6****FIG. 7****FIG. 8**
